United States Patent Office

Des. 195,792
Patented July 30, 1963

195,792

PUMP UNIT

Carl-Arne Breger, Stockholm, Sweden, assignor to Jon-
kopings Mekaniska Werkstads Aktiebolag, Jonkoping,
Sweden

Filed Jan. 22, 1962, Ser. No. 68,407

Claims priority, application Sweden Sept. 18, 1961

Term of patent 14 years

(Cl. D65—1)

FIG.1

FIG.2

FIG.3

FIG.4

FIG. 1 is a front perspective view of a pump unit embodying my new design;

FIG. 2 is a perspective view thereof taken from the left of FIG. 1;

FIG. 3 is a perspective view thereof taken from the right of FIG. 1; and

FIG. 4 is a bottom plan view thereof.

The fragmentary grid-like texture in FIGS. 1, 2, and 3 covers the entire areas designated.

I claim:

The ornamental design for a pump unit, as shown and described.
